ADJUSTABLE GARMENT HANGER

James L. Whitsel, Denver, Colo.

Application June 9, 1948, Serial No. 31,970

5 Claims. (Cl. 223—89)

1

This invention relates to garment hangers of the general type commonly employed for the non-wrinkling suspension and storage of coats, jackets, blouses, and the like, and more particularly to garment hangers susceptible of selective expansion and contraction in size for specific adaptation to use with particular garments, and has as an object to provide an improved such size-variable garment hanger.

As a further object of the invention is to provide an improved construction and operative interrelation of elements constituting a size-variable garment hanger.

As a further object of the invention is to provide improved selectively-manipulatable means actuatable for the contraction or expansion of a size-variable garment hanger.

As a further object of the invention is to provide an improved size-variable garment hanger susceptible of selective expansion or contraction in width and depth without alteration of the garment-supporting conformation of the hanger.

As a further object of the invention is to provide an improved size-variable garment hanger of low initial cost, susceptible of convenient size-varying adjustment, rugged and durable in use, and characterized by a relatively wide range of size variation.

With the foregoing and other objects in view, my invention consists in the construction, arrangement, and combination of elements herein-after set forth, pointed out in my claims, and illustrated by the accompanying drawing, in which—

Figure 1 is a side elevation of a typical embodiment of the invention as extended and expanded to maximum size. Figure 2 is a side elevation of the arrangement shown in Figure 1 as contracted to minimum size. Figure 3 is a cross section, on an enlarged scale, taken substantially on the indicated line 3—3 of Figure 2. Figure 4 is a cross section similar to Figure 3 illustrating an alternative construction and arrangement of the elements shown in said latter view. Figure 5 is a fragmentary, detail section, on an enlarged scale, through cooperating elements constituting a selectively-shiftable connection employed in the device. Figure 6 is a cross section, on an enlarged scale, taken substantially on the indicated line 6—6 of Figure 1.

In the construction of the improvement as shown, numeral 10 designates a head block formed from any suitable, rigid material, such as wood, molded synthetic resins, or the like, to seat within and conformably support the neck

line of an upper garment in the manner customary to garment hangers. The block 10 is preferably of moderate, uniform thickness, of substantial width along its straight lower margin, of a depth somewhat less than its width, and convergently concave at its side margins upwardly from their intersection with the block lower margin to smooth emergence with the arc of a convex upper margin crown. An open hook 11, of any appropriate particular construction and design, fixedly engages in and projects upwardly on the vertical median line from the block 10 for engagement with and over any suitable fixed support for suspension of said block and associated elements in a customary manner.

Fixedly overlapping upon and secured to the concave side margins of the block 10, a pair of like, rigid arms 12, preferably of channel section, diverge oppositely and downwardly from said block at like angles with the vertical center line of the latter and in the lateral plane of the block to define sloped arms tangent to the block concave margins at an inclination suited for supporting engagement with and beneath the shoulder portions of an upper garment. The arms 12 are conveniently longitudinally curved through the length of their end portions engaged with the block 10, thereby to facilitate fixed association of the arm end portions with the concaved block margins, and the lengths of said arms extending outwardly and oppositely from the block 10 are straight in a disposition that presents the throats of their channels to open inwardly and downwardly relative to the assembly; the end projection or cross section of each arm 12 straight portion being such as to constitute a slide bearing whereof the lower wall is interrupted by the channel throat longitudinally thereof.

Slidably and reciprocably engaged in each of the arm 12 straight portions, an extension member 13 is provided in size and transverse shape to slidably fill the associated arm 12 channel for retention within the latter against relative displacement other than longitudinally thereof, each of the members 13 having a straight portion substantially equal in length to the associated arm 12 straight portion and an outer end curved inwardly and downwardly of the assembly to constitute a garment-engaging lateral terminal of the hanger. Fixed at their outer ends to and adjacent the inner ends of the members 13, slidably and telescopically complementary struts 14 and 15 are arranged at like angles with their respective members 13 to axially align in substantial parallelism with the straight lower

margin of the block 10, said struts being fixed or worked to engage through and slide freely within the channel throats of the arms 12 and to freely and telescopically reciprocate relative to each other in maintained alignment as they are shifted bodily in maintained parallelism with, toward and away from the block 10 lower margin. The struts 14 and 15 may be of metal directly secured, as by welding or brazing, to the associated members 13, or said latter members may be provided with integral projecting studs or sleeves 16 to which appropriate ends of said struts are secured in any suitable or desired manner. Similar to and paralleling the length-variable unit comprised from the struts 14 and 15, a second such unit constituted from telescopically reciprocable complementary struts 17 and 18, identical with the struts 14 and 15 save as to length, is fixed at its opposite ends to and bridges in spaced parallel relation with the unit 14—15 between the outer, curved ends of the members 13. As shown in Figure 3, the struts 17 and 18, or the like struts 14 and 15, may be coaxial elements circular in cross section, in which case one of the struts is tubular in a size to receive and slidably accommodate a complementary strut which may be either cylindrical or tubular. Alternatively, as shown in Figure 4, the aligned strut elements may be laterally arched in a coacting conformation of hollow, channel-shaped, larger element and relatively smaller inner element receivable therein.

The organization thus far described completes a size-variable garment hanger wherein the members 13 may be manually extended from or retracted within their mounting arms 12 to adjust the vertical depth and horizontal width of the assembly, the coaxial elements of the telescopic strut units sliding relative to each other for variation in the unit lengths proportioned to the extension or retraction of the members 13. However, when friction of the engaged elements alone is relied upon to maintain the organized assembly and to retain an adjusted relationship of the assembly elements, the practicality of the device is less than adequate since the influence of gravity and the weight of supported garments may readily alter any adjustment made and may in fact operate to wholly withdraw the members 13 from the arms 12 with consequent disintegration of the unit. Further, with the elements of the organization only frictionally interengaged for selective manual adjustment, it is difficult to move the members 13 correspondingly and uniformly relative to their slide bearing engagement with the arms 12 without undesirable misalignments and binding of the slidable associations.

Completing the organization to facilitate size-variation of the unit and to hold the relatively-movable elements in any position of their adjustment, a feed-screw 19 is disposed inwardly adjacent and to parallel the straight portion of each arm 12 with its upper and inner, unthreaded shank rotatably received in a bore formed for such purpose within and in intersecting relation with the lower margin of the block 10, said screw having a length approximating that of the adjacent arm 12. A slot 20 opens through the thickness of the block 10 perpendicular to the axis of each screw 19 so that the shank of each feed screw traverses one of the slots 20, and a thumb-nut 21 is accommodated in each slot 20 in fixed relation with the screw 19 shank portion traversing the slot and serves to hold the associated screw against axial displacement in either direc-

tion relative to the block 10 while providing convenient means for the selective manual rotation of said screw. At their threaded ends remote from the block 10, the screws 19 engage through internally-threaded bores formed coaxially with the screws through the ends of the struts 14 and 15 secured to their respective members 13, so that rotation of said screws through the agency of the nuts 21 operates, according to the thread pitch and direction of screw rotation, to move the members 13 longitudinally relative to their mountings in the arms 12. Obviously, it is convenient to oppositely pitch the threads of the separate screws 19 so that a natural simultaneous rotation thereof in opposite directions will be productive of like shifting effect on the movable elements of the assembly, and it is further apparent that adjustment of the movable elements is accomplished through simultaneous rotation of both screws 19 to obviate binding distortion of the movable elements. When and as the screws 19 are actuated to retract the members 13 within the arms 12, the strut units correspondingly shorten in length as the complementary elements thereof telescope relative to each other, and as said screws are actuated to extend the members 13 from the arms 12, the strut units correspondingly lengthen through axial outward displacement of their complementary elements; said strut units thus automatically reacting to the shifting of the members 13 without impairment of their character or function.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A garment hanger comprising a suitably-shaped head block formed with upwardly-converging, oppositely-concaved, side margins, hollow, longitudinally-slotted arms end-secured to said block side margins to diverge as straight lengths outwardly and downwardly therefrom with their slots in opposition, an extension member slidably accommodated within and for reciprocation longitudinally of each said arm, telescopic, length-variable strut units end-fixed adjacent the ends of and to bridge in spaced, parallel relation between said members with the ends of the inner said unit slidably engaging through the arm slots, and means operatively engaging between said block and ends of the inner strut unit selectively actuatable to position and adjust said members and struts relative to said arms and block.

2. A garment hanger comprising a suitably-shaped head block formed with upwardly-converging, oppositely-concaved, side margins, hollow, longitudinally-slotted arms end-secured to said block side margins to diverge as straight lengths outwardly and downwardly therefrom with their slots in opposition, an extension member slidably accommodated within and for reciprocation longitudinally of each said arm, telescopic, length-variable strut units end-fixed adjacent the ends of and to bridge in spaced, parallel relation between said members with the ends of the inner said unit slidably engaging through the arm slots, feed screws rotatably and non-reciprocably mounted in said block inwardly adjacent and to parallel said arms in threaded outer

end engagement through member-attached ends of said inner strut unit, and manually-actuatable means for the selective rotation of said screws.

3. In a garment hanger having a head block and a pair of like hollow arms end-secured thereto to diverge as straight lengths outwardly and downwardly therefrom in a common plane, opposed slots longitudinally intersecting adjacent inner walls of said arms, an extension member slidably accommodated within and for reciprocation longitudinally of each said arm, telescopic, length-variable strut units end-fixed adjacent the ends of and to bridge in spaced, parallel relation between said members with the ends of the inner said unit slidably engaging through said slots, and means operatively engaging between said block and ends of the inner strut unit selectively actuatable to position and adjust said members and struts relative to said arms and block.

4. In a garment hanger having a head block and a pair of like hollow arms end-secured thereto to diverge as straight lengths outwardly and downwardly therefrom in a common plane, opposed slots longitudinally intersecting adjacent inner walls of said arms, an extension member slidably accommodated within and for reciprocation longitudinally of each said arm, telescopic, length-variable strut units end-fixed adjacent the ends of and to bridge in spaced, parallel relation between said members with the ends of the inner said unit slidably engaging through the arm slots, feed screws rotatably and non-reciprocably mounted in said block inwardly adjacent and to parallel said arms in threaded outer end engagement through member-attached ends of said inner strut unit, and manually-actuatable means for the selective rotation of said screws.

5. In a garment hanger having a head block, a pair of like hollow arms end-secured to said

block to diverge as straight lengths outwardly and downwardly therefrom in a common plane, opposed slots longitudinally intersecting adjacent inner walls of said arms, an extension member slidably accommodated within and for reciprocation longitudinally of each said arm, and telescopic, length-variable strut units end-fixed adjacent the ends of and to bridge in spaced, parallel relation between said members with the ends of the inner said unit slidably engaging through the arm slots, means manually and selectively actuatable to position, extend, and retract said members and struts relative to said arms and block, said means comprising a feed screw end-mounted for rotation in said block and projecting therefrom in inwardly-adjacent, spaced parallelism with each said arm to underlie the arm slot, a slot opening through said block perpendicular to each screw mounted end and traversed thereby, a thumb-nut fixed to each screw mounted end within the slot traversed thereby coactable with the associated slot margins to limit axial displacement of its screw, and threaded holes through outer end portions of the inner strut unit aligned with and cooperatively engaging the ends of said screws remote from said block.
